[57] **ABSTRACT**

An attenuator or pad device which has an outer conductor in the form of a generally T-shaped body, formed with an interior cavity extending longitudinally therethrough. The cavity is also generally T-shaped in configuration having one part in the form of a double-ended exponential horn having its apex or smallest diameter at the center of the tubular body and extending continuously exponentially outwardly therefrom in opposed longitudinal directions to the outer ends of said body.

A second part of the cavity forming the stem thereof is also generally exponential in form extending from the bottom of said stem outwardly and upwardly to communicate with the double-ended cavity part at its center.

An elongated resistance element defining the inner conductor of the attenuator or pad extends centrally through the cavity and provides an impedance pad which has the same input and output magnitude whereby the device may be utilized as an interstage coupling device.

T-ATTENUATOR OR COUPLING NETWORK HAVING AN IDENTICAL CHARACTERISTIC IMPEDANCE FROM EITHER END

A primary object of the present invention is to provide a new and novel attenuator or pad device that is especially designed to provide for interstage impedance coupling between two successive electronic stages.

Another object of the present invention is to provide a new and novel attenuator or pad device especially designed as an interstage coupling device and which has an identical characteristic impedance from either coupling end of the device.

Additional objects and advantages of the attenuator or pad device of the present invention will be apparent to one skilled in the art and upon reference to a preferred embodiment thereof as is described in the following specification and illustrated in the accompanying drawings wherein:

FIG. 1 is a side view in elevation of the attenuator or pad device embodying the present invention;

FIG. 2 is an end view taken an approximately the line 2—2 of FIG. 1;

FIG. 3 is a longitudinal sectional view taken on line 3—3 of FIG. 2; and

FIG. 4 is a schematic diagram of the effective circuit of the attenuator device.

Referring now to the drawings, as shown particularly in FIGS. 1 and 3, the attenuator or pad device of the present invention includes an elongated tubular body 10 generally T-shaped in overall configuration formed of a suitably conductive material such as steel and defining a first or cross-bar part 12 and a second or stem part 14.

The first body part 12 is provided with an internal cavity 16 which extends generally centrally longitudinally therethrough, and is of a double-ended exponential horn configuration. The apex 17 of the horn-type cavity is located at the center of the body 10, the wall thereof extending exponentially outwardly toward the opposed longitudinal ends to an end cavity portion 18 of constant diameter.

The stem part 14 of the body 10 is also formed with an internal cavity as shown at 20 which extends centrally longitudinally therethrough being single-end exponential horn-like in configuration with the wide end of the horn communicating with the apex 17 of the aforesaid horn cavity 16.

A suitable resistance element, being generally tubular in form as identified at R, and which may be made of any suitable material merely for example a ceramic base material having a resistance material deposited on the surface thereof, may be disposed in the cavity 16 extending centrally therethrough being thus equally spaced from the cavity wall.

As seen at 22, end caps formed of any suitable insulating material may be disposed in the end cavity portions 18 and into which the ends of said resistance element R may be disposed being thus effective to retain the same centrally within the cavity 16.

A second resistance element as identified at T may be similarly disposed in the cavity 20 of the body part 14, an end thereof projecting into the apex part 17 of the horn cavity 16 and suitably rigidly attached to the resistance element R at its center point.

The stem part 14 of the body 10 is provided with an up-standing rim 24 surrounding the adjacent end of the cavity 20 and provides support for the end of the resistance element T disposed therein.

The resistance material is deposited by any suitable method upon the surface of the rod elements R and T being distributed thereover and connected together at the juncture of the said rod elements to form a T-network comprising resistances R, and R₂ as shown in FIG. 4.

The stem part of the body may be threaded as seen at 24a which may enable a suitable cap 26 to be placed thereover to effectively seal the cavity 20 at said one end. The body of the device may also be provided with a threaded port 28 which opens to the apex 17 of the horn cavity 16 directly opposite

the communicating end of cavity 20, and which may be used to facilitate assembly of the device and connection thereof into an electronic circuit.

The input end of the attenuator or pad device may be terminals t₁ and t₃, and the output end similarly identified at t₂ and t₃. By attaching conductors to each of said terminals t₁ and t₂, and connecting t₃ to the body 10, the attenuator or pad device may be used as an interstage coupler; terminals t₁ and t₃, representing the input of said attenuator and terminals t₂ and t₃ the output thereof. Terminal t₃ may be used as the circuit ground or neutral conductor. The resistance elements R and T with the aforesaid terminal connections defines the inner conductor of the attenuator or pad, and the body 10 the outer conductor of said device.

With the resistance values R₁ and R₂ assigned, it will also be realized that the characteristic impedance Z₀ looking in either direction — input or output — is equal.

Likewise, the series inductive and shunt capacitive characteristics of the attenuator or pad at points intermediate the ends of the device vary exponentially between the desired end impedances designed for the said device.

As is further understood, the inductance of the attenuator or pad varies directly as the logarithm of the spacing between the center conductor R₁, R₂ and the body 10 representing the outer conductor — the wall of cavity 16 varying exponentially and decreasing in spacing toward the apex 17. Likewise, the capacitance varies inversely as the logarithm of the aforesaid spacing between said conductors. In like manner, the inductance of the section of the pad represented by resistance

R₃ in the stem cavity 20 varies directly as the logarithm of the spacing between the center conductor R₃ and the wall defining said cavity 20 which is seen to vary exponentially from the apex 17 of horn cavity 16 and decreasing to the upper end thereof as seen in FIG. 3. Also, the capacitance of this pad section varies inversely as the logarithm of the aforesaid spacing between said conductors.

Having thus described a preferred embodiment of attenuator or pad device of the present invention, it will be apparent to one skilled in the art to which it pertains that this invention may be changed and/or modified without departing from the inventive concept as are defined in the claims.

What is claimed is:

1. An attenuator or pad for providing interstage coupling comprising a body formed of conductive material, means defining a double-ended exponential horn in said body and extending longitudinally therethrough with the apex of said horn being at the center of the body, means in said body defining a single-ended exponential horn extending transversely of the double-ended horn and connecting at its larger end with the apex of the double-ended horn, first resistance means extending centrally through the double-ended horn, second resistance means extending centrally through the single-ended horn, one end of the second resistance means connecting with the first resistance means at the apex of the double-ended horn to thereby form a T-network having a shunt resistor and two series resistors equal to each other, the opposite end of the shunt resistor being defined as the common terminal of the T-network, the free end of each of the series resistors representing an input terminal and an output terminal respectively of said T-network which together with the common terminal define the input end and the output end of the network, the impedance of each series resistor of the T-network as determined by the spacing between the series resistor and its associated surrounding wall of the double-ended horn varying exponentially and in a decreasing magnitude incrementally toward the apex of the horn and the impedance of the shunt resistor of the T-network as determined by the spacing between said shunt resistor and its associated surrounding wall of the single-ended horn varying exponentially and in an increasing magnitude incrementally toward the apex whereby the T-network has an identical characteristic impedance from either end.
